UNITED STATES PATENT OFFICE.

SIMON OTTINGER, OF NEW YORK, N. Y.

DESIGN FOR A WOMAN'S SUIT.

43,774.

Specification for Design.

Patented Apr. 1, 1913.

Application filed June 12, 1912. Serial No. 703,312. Term of patent 7 years.

To all whom it may concern:

Be it known that I, SIMON OTTINGER, a citizen of the United States; and a resident of the borough of Manhattan, in the city, county, and State of New York, have invented a new, original, and ornamental Design for Women's Suits, of which the following is a specification, reference being had to the accompanying drawing, forming a part thereof.

The figure is a perspective view of a suit showing my new design.

I claim:

The ornamental design for a woman's suit, as shown.

In witness whereof I have hereunto signed my name in the presence of two subscribing witnesses.

SIMON OTTINGER.

Witnesses:

F. R. GEORGE,
MAX SECKENDORF.
